UNITED STATES PATENT OFFICE.

THEODORE SAUNDERS, OF DANBURY, CONNECTICUT.

PRESS FOR CAR-SEALS.

SPECIFICATION forming part of Letters Patent No. 406,114, dated July 2, 1889.

Application filed August 16, 1888. Serial No. 282,905. (No model.)

To all whom it may concern:

Be it known that I, THEODORE SAUNDERS, a citizen of the United States, residing at Danbury, in the county of Fairfield and State of Connecticut, have invented certain new and useful Improvements in Presses for Car-Seals; and I do hereby declare the following to be a full, clear, and exact description of the invention, such as will enable others skilled in the art to which it appertains to make and use the same.

My invention relates to certain new and useful improvements in presses for upsetting the wire of lead car-seals and impressing said seals with the usual inscription, and is especially applicable for use in connection with seals of the construction shown and described in another application for Letters Patent filed by me on an even date herewith, its object being to provide an exceedingly simple and durable device of this description, by which the seal may be readily applied.

With these ends in view my invention consists in the details of construction and combination of elements, hereinafter set forth, and then specifically designated by the claims.

In order that those skilled in the art to which my invention appertains may understand how to make and use the same, I will proceed to describe its construction and operation in detail, referring by letter to the accompanying drawing, forming a part of this specification, which represents my improvement in sectional elevation.

A denotes the upper or stationary lever, the forward end of which terminates in arms B C, and D is a presser-lever pivoted at *a* to the side of the arm C in such manner that its free end has a vertical movement between the forward ends of the arms B C, for the purpose presently explained.

E is a punch or bending-tool fitted within the lever D, so as to slide in its bearing independent of said lever.

F is the actuating-lever, pivoted at *b* to the arm C, and provided near its fulcrum with operating or cam surfaces *c d*, which successively actuate the punch and presser-lever on the upward movement of said lever F.

G is a strap pivoted to the lever D at *a* and embracing the actuating-lever in such manner that when the latter is distended the lever D will be brought to its normal position by said strap.

H is a spring interposed between the stationary lever and the actuating-lever F, for distending said lever.

A die I, provided with the usual inscription, is secured within the arm B, and an opening J, formed through the center of said die and arm, permits the displacement of the wire or lead in applying the seal.

From the foregoing description the operation of my improvement will obviously be as follows: The seal, shown in the above-referred-to application, having been placed upon its wire, is inserted between the die and punch, so that the openings or depressions in said seal will register with the punch. Now, by operating the actuating-lever against the resiliency of the spring the cam *c* will force the punch upward, thus upsetting the wire, until the cam *d*, by reason of its greater distance from the common fulcrum, overtakes the presser-lever D and moves it in advance of the punch to compress the seal between the said presser-lever and the die, for the purpose of imprinting the inscription on said die upon the seal. Upon releasing the actuating-lever the spring H returns said lever to its normal position, and, through the strap G, depresses the presser-lever and withdraws the punch.

Having thus fully described my invention, what I claim as new and useful is—

1. In an implement of the character described, the stationary lever provided with two arms, in combination with a presser-lever pivoted to the lower of said arms and carrying a punch capable of sliding in said presser-lever independent thereof, and an actuating-lever pivoted to said lower arm of said stationary lever and provided with cam-surfaces adapted to first operate the punch and then the presser-lever, as specified.

2. In an implement of the character described, the stationary lever terminating in two arms, one adapted to imprint a seal, the

other forming bearings for the movable parts of the device, in combination with the lever D, pivoted to the latter arm, the punch carried by said lever, the actuating-lever adapted to operate the lever D and punch, a spring for distending the actuating-lever, and a strap connected to the lever D and embracing said actuating-lever, as and for the purposes specified.

In testimony whereof I affix my signature in presence of two witnesses.

THEODORE SAUNDERS.
